UNITED STATES PATENT OFFICE.

CYRIL CHAS. SLAPNICKA, OF MILWAUKEE, WISCONSIN.

HYDROCARBON-BURNER.

1,175,187.

Specification of Letters Patent. Patented Mar. 14, 1916.

Application filed November 15, 1915. Serial No. 61,667.

To all whom it may concern:

Be it known that I, CYRIL C. SLAPNICKA, a citizen of the United States, residing at Milwaukee, in the county of Milwaukee and State of Wisconsin, have invented certain new and useful Improvements in Hydrocarbon-Burners, of which the following is a specification.

This invention relates to certain new and useful improvements in hydrocarbon burners.

The primary object of the invention is the provision of a burner especially adapted for employing for fuel such well-known hydrocarbons commonly termed kerosene and coal-oil, the burner being arranged for vaporizing the hydrocarbon prior to the ignition thereof.

A further object of the device is the provision of a kerosene burner adapted to vaporize the oil and to spread the combustible vapor over a large area for providing an extensive burning surface, the same being arranged with air mixing means.

A still further object is to provide an alcohol heater for a hydrocarbon burner for supplying the initial vaporization of the fuel, the burning vapor effecting a continuance of vaporizing of the fuel during the operation of the device.

With these general objects in view and others that will appear as the nature of the invention is better understood, the same consists in the novel construction, combination and arrangement of parts hereinafter more fully described, illustrated in the accompany drawings, and then claimed.

In the drawings forming a part of this application and in which like designating characters refer to corresponding parts throughout the several views:—Figure 1 is a vertical transverse sectional view through the device partly in elevation, and, Fig. 2 is a top plan view of the device.

It being understood that any of the fluid hydrocarbons may be employed as fuel in the present burner, an inlet or service pipe 10 for the fuel is illustrated as tapped into an upright supporting tube 11 of a generator or retort 12, the said tube 11 being mounted upon a stationary supporting base 13.

The burner 14 comprises a cup-shaped casing 15 positioned directly beneath the generator 12 upon oppositely-positioned supporting posts 16 and 17 while a cover plate

18 is mounted upon the casing 15 and provided with jet perforations or outlets 19 for the vaporized fuel.

The generator 12 is in the form of a spider 60 having radially-extending arms 20 provided with terminal closure plugs 21 and is in axial alinement with the cover plate 18 as well as a depending neck 22 carried by and opening into the casing 15 at a point between the posts 16 and 17. 65

An L-shaped burner pipe or tube 23 communicates with an extended arm 24 of the generator 12 and has an upturned outlet end 25 projecting axially within the open lower 70 end of the burner casing neck 22 and having a perforated jet cap 26 mounted upon the top thereof.

A baffle or distributing member 27 is removably positioned within the casing 15 75 resting upon the bottom 28 of the said casing by means of a plurality of feet 29 and spaced from the sides of the casing a uniform distance by means of laterally projecting lugs 30, it being understood that the distributor 80 will thus be arranged axially of the neck 22 for receiving upon its bottom the impact of the combustion mixture rising through the neck 22. The distributor 27 is here illustrated hollow in form for lightness although 85 the same may be constructed of solid metal if desired, it being only essential that the distributor 27 be spaced substantially equal distances from the sides, top and bottom of the casing 15. 90

An alcohol burner in the form of a pan 31 is arranged for initially starting the vaporization of the hydrocarbon fluid and has a radially-disposed arm 32 by means of which the said alcohol burner is pivotally 95 mounted upon an upwardly-extending arm 33 of the post 17.

The pan 31 is filled with a desirable wicking, such as asbestos packing 34 which upon being saturated with alcohol and ignited 100 may be swung beneath the generator 12 where the same will heat and vaporize the hydrocarbon within the generator 12 and its arms 20 which has been admitted thereto through the service pipe 10 under control of 105 a valve not shown. The vapor thus formed is conducted by the pipe 23 and extension 25 through the jet cap 26 where the same is mixed with air entering through the open end 35 of the neck 22 and upon contacting 110 with the baffle 27 spreads out around the same and escapes through the outlet perfo-

rations 19 of the burner plate 18 where the same is ignited and furnishes an expanse of flame substantially co-extensive with the cover plate 18. The continued burning of 5 the vapor above the plate 18 maintains the generator 12 in its operative heated condition to continue the vaporization of the hydrocarbon which is fed thereto from the service pipe 10 so that the vapor continues to 10 be fed through the jet cap 26 as long as the service pipe valve remains open and during the operation of the burner. The position of the baffle 27 allows an equal distribution of the combustible mixture to the cover plate 15 18 so that a uniform heating blaze is provided thereabove, thus assisting the combustion of the mixture. By reason of the pivotal mounting of the alcohol burner 31, the same may be readily swung out of 20 operative position and again re-positioned whenever desired.

While the form of the invention herein shown and described is what is believed to be the preferred embodiment thereof, it is 25 nevertheless to be understood that various forms, modifications and arrangements of the parts may be made without departing from the spirit and scope of the invention as claimed.

30 What I claim as new is:—

1. A burner comprising a cup-shaped casing having a depending entrance neck, a perforated cover plate for the said casing, a baffle positioned within the said casing in 35 substantially equal spaced relations with the bottom and sides thereof and the said cover plate, and a hydrocarbon conduit traversing said plate and extending inwardly of the said neck.

40 2. A burner comprising a casing, a perforated gas outlet cover plate for the said casing, a baffle of smaller dimensions than said casing positioned therein with the top and bottom walls thereof being spaced from 45 the casing and parallel therewith, a vapor generator positioned above the said plate, an entrance feed pipe projecting from the said generator and communicating with the said casing, and an initial heating means 50 for the said generator.

55 3. A burner comprising a cup-shaped casing having a downwardly-extending air mixing neck, a perforated vapor outlet cover plate for the said casing, a hydrocarbon conduit traversing the said plate in spaced relations thereto and centrally projecting within the said neck, an initial vaporizing means swingingly supported between the

said generator and plate, a baffle within the casing positioned between the cover plate 60 and said neck, and means for holding the baffle in spaced relation to said casing.

4. A burner comprising a cup-shaped casing having a downwardly-extending air mixing neck, a perforated vapor outlet cover 65 plate for the said casing, a hydrocarbon conduit traversing the said plate in spaced relations thereto and centrally projecting within the said neck, radial arms carried by said conduit centrally of said casing, a baffle 70 member positioned within the said casing and equally spaced from the walls thereof, a supporting arm, a pan pivotally carried by the said arm and having a path of movement between the said plate and conduit, 75 and a wick member within the said pan.

5. A device of the class described, comprising a burner casing, a vapor generator including radial arms in axial alinement with the said casing and positioned there- 80 above, a fuel supply pipe for the said casing extending from the said generator, and a hollow baffle member within the said casing equally spaced from the sides thereof.

6. A device of the class described, comprising a burner casing, a vapor generator in axial alinement with the said casing and positioned thereabove, a fuel supply pipe for the said casing extending from the said generator, a hollow baffle member within the 90 said casing equally spaced from the sides thereof, supporting posts for the said casing, an air intake member for the said casing, and a pivotally mounted initial heating means adapted to be positioned between the 95 said casing and generator.

7. A device of the class described, comprising a burner casing, a vapor generator in axial alinement with the said casing and positioned thereabove, a fuel supply pipe 100 for the said casing extending from the said generator, a hollow baffle member within the said casing equally spaced from the sides thereof, supporting posts for the said casing, an air intake member for the said casing, an 105 upright arm carried by one of the said posts, a pan-shaped burner pivoted upon the said arm and having a path of movement between the said generator and casing, and a wick within the pan-shaped burner.

110 In testimony whereof I affix my signature.
